CLAIM

The ornamental design for a dog house, as shown and described.

DESCRIPTION

FIG. 1 is a front, right and top perspective view of a dog house showing my new design;

FIG. 2 is a rear, left and bottom perspective view thereof; FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view thereof; taken from the encircled portion 9 in FIG. 1;

FIG. 10 is an enlarged view thereof; taken from the encircled portion 10 in FIG. 2; and,

FIG. 11 is an enlarged view thereof; taken from the encircled portion 11 in FIG. 2.

The dash-dash broken lines in the drawings depict portions of the dog house and form no part of the claimed design. The dash-dot-dash broken lines in the drawings are included to indicate a partially enlarged view and form no part of the claimed design.

1 Claim, 11 Drawing Sheets
